UNITED STATES PATENT OFFICE.

SAMUEL CLINE, OF PHILADELPHIA, PENNSYLVANIA, ASSIGNOR TO GEORGE A. REACH, OF BALA, PENNSYLVANIA.

HEAD-PROTECTOR.

1,112,358.

Specification of Letters Patent. Patented Sept. 29, 1914.

Application filed April 18, 1914. Serial No. 832,915.

To all whom it may concern:

Be it known that I, SAMUEL CLINE, citizen of the United States, residing at Philadelphia, Pennsylvania, have invented certain new and useful Improvements in Head-Protectors, of which the following is a specification.

This invention relates to protectors for the head and its particular object is to provide a protector for the face and ears that a boxer can wear when in training to allow his trainer to hit him about the head without fear of injury about the ears, eyes or chin, and is particularly useful when an ear has been injured as is common with boxers.

The invention consists in the features of construction and arrangement and combination of parts hereinafter described and particularly pointed out in the claims.

20 The invention is illustrated in the accompanying drawings in which—

Figure 1 is a perspective view of the invention, and Fig. 2 is a sectional view showing the metal ear piece.

25 The protector is preferably made of some such material as buckskin or soft leather with a soft material as felt, or felt and canvas, to better protect the face of the wearer. 1 indicates the leather outside and 30 2 the lining. Openings are provided for the wearer's eyes at 3 and for the nose at 4. The leather and the lining are stitched together around the edges of the protector and the openings 3 and 4. Along the top 35 edge a binder 5 is stitched on the outside of the leather. Darts are made at 6 and 7 to make the protector fit around the chin of the wearer. Secured between the binding 5 and the leather at the middle point of the 40 protector is a strip of the binding material 8 provided with loops at 9, 10 and 11 for the purpose hereinafter described. A strap 12 and a buckle 13 are secured between the binder 5 and the leather as indicated. The

extremities of the binder 5 terminate in a 45 strap and buckle as shown at 14 and 15. Another strap 16 and buckle 17 is provided, secured between the leather and the lining.

In Fig. 2, it can be seen how the strip 8 passes over the head of the wearer and the 50 strap 12 passes through the loop 9 to be buckled over the boxer's head by the buckle 13. Again, the strap 14 passes through the loop 10 and is buckled over the head at 15 and similarly the strap 16 passes through 55 the loop 11 to meet the buckle 17. Each strap being provided with holes so that with the corresponding buckle, the protector can be adjusted in three places to better fit the head of the wearer. At 18 secured to 60 the underside of the leather is a metallic ear protector or guard 20 for which the felt is cut away to permit the ear of the boxer to enter. It may be made of any suitable metal and is of a shape to fit over the ear. 65 Ventilating holes may or may not be provided to allow the wearer to hear, as indicated at 19, and they may extend all the way through the leather. Again, the protector may be made with only one ear piece if it 70 is so desired.

I claim as my invention:

1. A mask for training purposes comprising a soft yielding protector to the face and ears, with nose and eye openings, and a 75 metallic protector inserted in the pad for the ears, substantially as described.
2. A mask for training purposes comprising a protector for the face, a lining therefor, a metallic ear guard between the lining 80 and the protector, and an opening in the lining registering with the ear guard.

In testimony whereof, I affix my signature in presence of two witnesses.

SAMUEL CLINE.
